S. J. SHEPARD,
MEANS FOR SECURING HEADS TO HANDLES OF TOOLS,
APPLICATION FILED OCT. 31, 1919.

1,342,929.

Patented June 8, 1920.

Inventor:
Stanley J. Shepard,
by A. B. Verlissel, His Attorney.

UNITED STATES PATENT OFFICE.

STANLEY J. SHEPARD, OF PORTERVILLE, CALIFORNIA.

MEANS FOR SECURING HEADS TO HANDLES OF TOOLS.

1,342,929.

Specification of Letters Patent. Patented June 8, 1920.

Application filed October 31, 1919. Serial No. 334,817.

To all whom it may concern:

Be it known that I, STANLEY J. SHEPARD, a citizen of the United States, residing at Porterville, in the county of Tulare and 5 State of California, have invented certain new and useful Improvements in Means for Securing Heads to Handles of Tools, of which the following is a specification.

The heads of tools, such as hammers, 10 hatchets, axes, sledges and the like, are during use of the tools, liable to become loose on the handles thereof. It is also at times desirable or necessary to replace worn handles with new ones. In replacing the handles heretofore in general use, it was almost 15 always necessary to whittle the entering portions of the handles so as to fit into the bores of the heads. This whittling is an arduous task, owing to the hardness of the wood employed for handles of this character.

It is the object of my invention to provide convenient novel means whereby handles are fastened in the heads of tools of the character mentioned; further, to provide 20 novel means whereby the entering ends of the handles are arranged to fit a wide range of differences in sizes of bores in the head; and, further, to provide novel means whereby the handle is readily tightened in the 25 head from time to time, so that the handle may be continuously held firmly in the head in order that wear and abrasion between the head and handle are avoided, and splitting, breaking and injury to the handles 30 are prevented.

It is the object of my invention, further, to provide novel means whereby to secure a firm joint between the head and the handle, and whereby the joint may be adjusted conveniently so as to obtain a firm clamping fit 35 between the handle and the head, and to maintain such firm joint.

The invention will be further readily understood from the following description 40 and claims, and from the drawing in which latter:

Figure 1 is a side elevation of my improved device, partly in section on the line 1—1 Fig. 2.

50 Fig. 2 is an end view of the same.

Fig. 3 is a cross-section of the same, taken on the line 3—3 of Fig. 2.

Fig. 4 is an edge elevation of the head-end 55 of the handle, the head being omitted; and,

Fig. 5 is a perspective view of the anchor,

wedge and adjusting screw of the clamping means in assembled relation.

11 represents the handle and 12 the head. The head is exemplified as the head of a machinist's hammer. The tool to which my invention is applied may however be any other tool to which the same is applicable.

The head-end of the handle is received in a bore 14 in the head. The side walls 15 of this bore preferably diverge toward the 65 outer end of the bore as exemplified in Fig. 3. The end walls 16 of the bore are shown parallel. The end walls of the bore are preferably rounded in cross-section. The end of the handle received in the bore is provided with a slot 17, extending lengthwise 70 of the handle, to form the head-end of the handle into branches 18 integral with the body of the handle.

A wedge-piece 21 is received in this slot. 75 The slot may be of wedge-form if desired. The handle is preferably of wood and the wedge-piece is preferably of metal. The base of the wedge is toward the outer end of the head, the apex of the wedge being directed 80 toward the grasping end of the handle.

An anchor 24 is located in the handle. A screw 25 is swiveled, as by a swiveled joint 85 26, to the anchor. The anchor and the screw are located in a bore 27, extending lengthwise in the handle. The axis of the bore and the axis of the handle are preferably coincident. The slot 17 for the wedge preferably 90 merges into the bore.

The screw is provided with turning means at its outer end. These turning means are shown as a slotted head 29, but may be of other desirable form. The screw has threaded connection in a threaded bearing 95 30 in the wedge-piece. This threaded bearing is shown as an enlargement in the side walls of the wedge and is received in the bore. A pin 31 is received through a hole 32 in the anchor and is preferably received 100 through holes 33 in the handle and holes 34 in the head 12. The ends of the pin are shown riveted into countersunk recesses 36 in the head, forming heads 37 on the ends of the anchor-pin for holding the same in 105 place.

The anchor is fixed in endwise relation in the handle, as by means of the pin 31 received in holes 33 in the handle, placed in suitable position adjacent the head-end of 110

the handle, but preferably so as to register with the holes 34 in the head. The screw has a swivel connection with the anchor and is permitted to turn. When the screw is turned, it forces the wedge lengthwise of the handle, in or out, according to the direction in which the screw is turned, and the direction in which the threads thereon extend. The anchor is anchored to the handle and preferably to the head to resist movements in both directions of force applied thereto. Forcing the wedge inwardly causes the branches 18 of the end of the handle located in the bore 14 of the head, to move laterally against the walls of the bore in the head, instanced as the side walls, so as to clamp the branches of the handle between the wedge and the walls of the bore in the head, for clamping the head to the handle.

In assembling the parts, the bore 27 is preferably formed in the head-end of the handle by a suitable boring tool and the anchor is inserted in the bore. The wedge 25 may be driven into the end of the handle for forming the slot 17 and the branches 18, or, if desired, this slot may be formed by means of a suitable saw for sawing the slot in the handle prior to the insertion of the wedge. The slot may be formed with parallel side walls or with side walls diverging outwardly, as may be desired. The wedge-piece is preferably at its outer limit of movement on the screw when it is inserted in the handle.

The head-end of the handle is inserted into the bore of the head. When so inserted it may, if desired, have been provided with its assembled anchor, screw and wedge, the wedge being at its outermost limit of movement, or if desired, the anchor, screw and wedge may be inserted in the handle-end after the insertion of the latter into the bore of the head.

When the handle-end has been located in the bore of the head, and the anchor, wedge and screw have been inserted in the bore in the end of the handle, so that the hole 32 in the anchor registers with the holes 33 in the handle, and the holes 34 in the head register with the holes 33 and 32, the anchor-pin 31 is inserted in said holes, and the ends of the anchor-pin riveted to the head, for assembling the parts. For convenience in assembling, the hole 32 in the anchor may be enlarged, the end walls of the hole limiting movement of the anchor.

After the parts are thus assembled, the screw 25 is turned for moving the wedge 21 inwardly, whereby the branches 18 of the head-end of the handle are pressed firmly upon the walls in the bore of the head which are opposed to the spreading walls of the

wedge, for clamping the parts together. The branches 18 may be spread by the 65 wedge-piece so that the outer end of the portion of the handle in the bore of the head is of greater diameter than the inner end of said portion for causing the outer faces of said branches to be divergent toward 70 their outer ends and forced into clamping connection with the preferably diverging walls of the bore in the head.

The screw 25 is readily turned from time to time for maintaining the clamping fit between the branches of the handle and the walls of the bore in the head, in order to avoid the head becoming loose on the handle, and to insure that the head is at all times fixed to the handle for avoiding abrasion and wear of the handle in the head, and preventing a slivering or splitting of the handle. The head 29 may be received in a recess 38 in the end of the handle, and the parts so arranged that the handle-parts 85 do not protrude beyond the outer edge of the head.

Having thus fully described my invention, what I claim as new and desire to secure by Letters Patent is:

1. In means of the character described, the combination of a head having a bore, a handle the end whereof is received in the said bore, an anchor in said handle, means for anchoring said anchor to said handle 95 and to said head, the end of said handle in said bore provided with a slot, a wedge-piece received in said slot, and a screw having swivel-connection with said anchor and threaded connection with such wedge-piece 100 whereby to move said wedge-piece lengthwise of said handle by rotation of said screw.

2. In means of the character described, the combination of a head provided with a 105 bore having opposite walls diverging outwardly, a handle the end whereof is provided with branches received in said bore, a wedge-piece in said handle between said branches, a screw having threaded connection with said wedge-piece, and means for holding said screw in lengthwise relation to said handle, said screw provided with means for turning the same, whereby to move said wedge-piece lengthwise in said handle to 110 spread said branches into clamping relation with said outwardly diverging opposite walls of said bore in said head.

In testimony whereof, I have hereunto signed my name in the presence of two sub- 120 scribing witnesses.

STANLEY J. SHEPARD.

Witnesses:

NORDICA DICKSON,
WALDO E. BURFORD.
